CLAIM

The ornamental design for an electrical metallic tubing to armored cable/metal clad cable duplex coupling, as shown and described.

DESCRIPTION

FIG. 1 is a rear perspective view of the electrical metallic tubing to armored cable/metal clad cable duplex coupling; FIG. 2 is a top view of the electrical metallic tubing to armored cable/metal clad cable duplex coupling; FIG. 3 is a bottom view of the electrical metallic tubing to armored cable/metal clad cable duplex coupling; FIG. 4 is a right side view of the electrical metallic tubing to armored cable/metal clad cable duplex coupling; FIG. 5 is a rear view of the electrical metallic tubing to armored cable/metal clad cable duplex coupling; FIG. 6 is a front view of the electrical metallic tubing to armored cable/metal clad cable duplex coupling; and, FIG. 7 is a front perspective view of the electrical metallic tubing to armored cable/metal clad cable duplex coupling showing the environment of the coupling in dashed lines. The broken lines shown represent unclaimed subject matter and form no part of the claimed design.
